UNITED STATES PATENT OFFICE.

ADOLPH LANGSNER, OF CHICAGO, ILLINOIS, ASSIGNOR TO EUGENE DIETZGEN COMPANY, OF CHICAGO, ILLINOIS, A CORPORATION OF DELAWARE.

DEVELOPING APPARATUS.

Application filed March 23, 1928. Serial No. 263,998.

My invention relates to apparatus for developing light sensitive material by the action of chemically active gas. In this particular instance, I have shown means for 5 developing a light sensitive paper such as the well-known ozalid paper by means of the action of ammonia gas.

One of the objects of my invention is to provide an apparatus containing two isolatable chambers, one constituting a developing chamber and the other constituting a loading chamber together with means forming a shiftable carrier adapted to be moved from the loading chamber into the developing 10 chamber, and reversely, there also being means for cutting off communication between the loading chamber and the developing chamber so that the source of chemically active gas present in the developing chamber 15 may be confined to said chamber during the developing action. An ancillary object of my invention resides in providing in the developing chamber a source of liquid adapted to evolve a chemically active gas, such for 20 instance as liquid ammonia, adapted to evolve ammonia gas, together with means for forcing or blowing air upon the liquid whereby to project the developing gas into contact 25 with the light sensitive material supported on the carrier within the developing chamber.

Another object of my invention is to provide my developing apparatus with the two chambers, the one a developing chamber and the other a loading chamber and to provide 30 a shiftable carrier which may be moved from one of said chambers to the other and further, to provide a movable door or partition which may be shifted so as to open or close communication between said chambers, permitting in the one instance the movement of 35 the carrier supporting the light sensitive material thereon from one chamber to the other for loading or developing, and in the other instance to close communication between said 40 chambers so that the developing action may take place solely in the developing chamber and the loading action and de-gasifying action may take place solely in the other chamber.

50 Still another object of my invention resides in providing a developing apparatus wherein the two separate chambers constituting the developing and loading chambers may be isolated one from the other by means 55 of a door or partition or may be put into

communication with each other by means of the shifting of said partition and wherein the developing chamber contains an opening provided with a plurality of shiftable shutters adapted to automatically be opened or 60 closed by the starting or stopping of the fan blower which is constructed and arranged to project the developing gas directly upon the light sensitive material supported within the developing chamber. Another object of this 65 aspect of my invention resides in the further provision of the loading chamber with a ventilating fan so that when the shiftable carrier supporting the light sensitive material is moved into the developing chamber and the 70 partition closed and the fan blower in the developing chamber started, the shutter will automatically open to permit a draft of air and the projection of the gas against the light sensitive material and thereafter when 75 the developing is completed, the motor for the fan may be reversed for automatically closing the shutters and the fan blower and at the same time begin to suck the ammonia 80 gas from the developing chamber back into its own chamber. In addition, when the light sensitive material, after being developed, is moved into the loading chamber and the partition shifted again to closed position, the fan blower in the loading chamber 85 may be operated to ventilate the developed material. Thus, it will be seen that I provide a developing apparatus comprising the developing in the loading chambers and comprising a partition adapted to permit communication between said chambers or to isolate the same and providing blowing devices 90 in each chamber, the one for developing the light sensitive material and the other for ventilating it, the construction being such 95 that the devices in the separate chambers are operable independently of the other.

Still another object of my invention resides in the construction of the trackage within the developing and loading chambers 100 and the arrangement of the shiftable partition adapted to be moved transversely through the tracks so as to shut off complete communication between the two chambers.

Still another object of my invention resides in the arrangement of the communicating loading and ventilating chambers and the movable carrier shiftable therebetween together with the mechanism for shifting 105 said carrier and the arrangement of a screen 110

or partition having slotted portions adapted to straddle the car shifting means so as to permit a substantially air-tight partition between the loading and ventilating chamber 5 while at the same time permitting the free operation of the car shifting means.

Still another object of my invention resides in the novel arrangement of means for supporting the light sensitive material from 10 the carrier and in a manner to permit its free insertion and quick withdrawal from the carrier.

Yet other objects of my invention reside in the details of construction of the cabinet 15 itself; the separate developing and ventilating chambers; the fan or blower chamber; the arrangement of the ventilating shutter for preventing the ingress of air to the blower; the means for driving the fan or blower; 20 the arrangement of the trackage between the developing and ventilating chambers, including the means for driving the wheeled truck or support along said trackage from one chamber to the other; the arrangement 25 of the partition or screen and the means for raising and lowering the same from a point outside of the apparatus; and in the general and specific arrangement of details not hereinbefore mentioned.

30 These and other objects of my invention will be apparent from a perusal of the following specification when taken in connection with the accompanying drawings in which:

35 Figure 1 is a front elevation of a preferred form of my apparatus;

Figure 2 is a plan sectional view taken on line 2—2 of Figure 1;

Figure 3 is a section taken on line 3—3 of 40 Figure 2 showing the curtain in lowered position;

Figure 4 is a section through the means for holding the light sensitive material; and

45 Figure 5 is a section on line 5—5 of Figure 4.

In general, my apparatus comprises a cabinet or the like providing two main chambers, a developing chamber and a loading and airing chamber. The developing chamber 50 is provided with an opening controlled by a plurality of relative light shutters, so light as to be automatically operable by a current of air created by a fan within the developing chamber so that when the fan 55 is operable in one direction, the travel of air will automatically cause the shutters to open whereas when the fan is reversed, it will cause the shutters to automatically close. In addition, there is disposed within the developing chamber a container of liquid 60 adapted to generate or evolve chemically active gas such for instance as a pan of ammonia adapted to generate ammonia gas and there are provided a plurality of wicks or 65 equivalent devices which dip into the am-

monia so that the wicks are saturated by capillary attraction. These saturated wicks are located directly in the path of the air projected by the blower so that when the fan is operated, the current of air will be forced 70 against the saturated wicks so that the ammonia gas will be given off more quickly and will be blown in the desired direction and if desired the direction may be guided by suitable partitions. The loading and developing chambers are adapted to communicate but may be closed by means of a shiftable curtain or partition preferably mounted on rollers and arranged so that when the curtain is raised, communication 80 is established between the loading and developing chamber and when the curtain is lowered the two chambers will be completely isolated the one from the other. The floors of the two chambers are provided 85 with a track which is slotted or divided to permit the passage of the curtain therethrough during the raising and lowering operations. A wheeled carrier is mounted to roll along this track to move from one chamber to the other when the partition is raised. This carrier supports uprights provided with means for holding a plurality of sheets of light sensitive material such as ozalid paper or the like. The loading chamber is provided with a relatively large door through which the paper holder on the truck may be loaded with light sensitive material to be developed or through which the already developed paper may be removed. In 95 addition, this loading chamber is provided with a fan blower having communication with the outside air so that when the blower is operated, the air will be forced in through the developed paper to ventilate it and to remove the occluded gases. Obviously during either the ventilating operation in the loading chamber, or the developing operation in the developing chamber, the partition between the two chambers is closed so 100 that the one operation will be entirely independent of the other. The blower fan in the developing chamber may be reversely driven so that on reverse movement instead of projecting the chemically active gas 105 against the light sensitive material as during the developing operation, the reverse movement of the fan will automatically close the shutters in the developing chamber and will suck the chemically active gas from the developing chamber back into the fan compartment so that when the partition is 115 subsequently raised very little, if any, of the developing gas will pass into the loading chamber.

120 Referring now to the details of my construction, I provide a cabinet upon suitable standards 2 which cabinet is of any desired shape and size but is preferably substantially rectangular so as to provide two relative- 125

ly large and communicable chambers. For instance, in Figure 1 the chamber 4 at the left is the loading chamber and the chamber 6 at the right is the developing chamber. The chamber at the right is provided on one side with an opening through which a square tubular housing 8 of sheet metal is fastened. This housing is provided with an end opening 10 in which are pivotally mounted as at 12 a plurality of shutters 14 of relatively light material. These shutters are adapted to overlappingly engage in closed position so as to completely close the opening 10 of this housing or hood 8. In addition, the upper and lower walls of the housing 8 are formed as bearings for a substantially vertical rod 16 having a turning head 18 at the outside of the casing 8 provided with a plurality of claws or fingers 20 within, which when the rod is turned will engage the separate shutters 14 and hold them in closed position. Within the housing 8, immediately to one side of the claws 20, I mount a bracket 22 having a central hub carrying a fan shaft 24 and a fan 26. The opposite end of the fan is provided with a band or driving connection 28 to a motor shaft 30 driven by a motor 32 located on the under side of the cabinet. This is a reversible motor so that the fan may be driven in reversed directions. Within the wall 34 of the ventilating chamber, I provide a tubular guide or housing 36 registering with the housing 8 and forming an extension thereof to provide a fan chamber and in this chamber I prefer to provide a plurality of air deflecting fans 38 which fan outwardly so as uniformly to deflect the air from the fan in desired directions and spread it so as to project the gas hereinafter described completely upon the light sensitive material supported within the developing chamber as hereinafter described. As forming a part of the fan chamber, and carrying the source of developing gas, I provide the interior of the developing chamber with partitions or walls 40 and 42 which provide a substantially central opening 44 directly opposite the housing 36. In the upper portion of this chamber, I provide a pan or container 48 containing a liquid adapted to evolve a chemically active gas such as liquid ammonia adapted to evolve ammonia gas. Similarly, I provide the lower portion of this fan chamber with another pan 50 likewise containing a quantity of liquid ammonia. I provide a saturating member adapted to have its ends immersed in the liquid in these pans. If desired, I may provide a plurality of wicks 52 or I may provide a single saturating member in the form of an open-work member having its upper and lower ends in the ammonia so as to draw the ammonia upwardly and down-

wardly by capillary attraction whereby the complete member will be saturated with the liquid ammonia.

Thus, when the fan is rotated in one direction the draft of air created thereby will automatically cause the very light shutters 14 to open and the current of air projected by the fan against the saturated wicks will cause the rapid evolution of developing gas which will be projected into the developing chamber proper. On the contrary, when the fan is driven in a reversed direction the current of air will cause the shutters 14 to be closed at which time they may be fastened in closed position by means of the rod 8 and the claws 20. At the same time, the reversed current of air will suck the chemically active gas from the developing chamber back into the fan chamber so as to remove as much of the developing gas from the developing chamber as is possible. During this time the partition or curtain hereinafter described will be in the lowered or closed position.

The loading or ventilating chamber 4 is provided at one side with a door 54 so that access may be had to the interior of this chamber for loading and discharging the light sensitive material. That wall of the chamber, preferably opposite the wall in which the door 54 is mounted is provided with an opening 56 and at the edges of this opening a bracket 58 is preferably mounted which bracket carries a shaft on which is revolvably mounted a fan or blower 60 driven by a belt 62 which in turn connects with a pulley on the fan shaft 24. A protective screening or housing 64 encloses the fan or blower 60. If desired, the fan 60 may be driven from a separate motor.

On the main floor 66 of the two chambers 4 and 6, I provide preferably two beams 68 and 70 on which I mount rails 72 and 74. These rails run the length of the two chambers except at the vertical plane in which the screen operates. At this point, the rails are slotted as at 76 to permit the screen to pass vertically and downwardly across the rails. This slot is sufficiently wide to permit this screen to pass through it while at the same time not interfere with the rolling of the carriage or truck along the rails.

The truck for supporting light sensitive material is of any desired construction. It preferably comprises a base 76 carrying axles 78 on which are mounted the typical car wheels 80 adapted to roll along the tracks 72 and 74. The base 76 of the truck has spaced uprights 82 and 84 at the four corners and a suitable number of cross braces 86 carrying a plurality of depending sheet holders. These holders, as shown in Figures 4 and 5 of the drawing, are preferably formed of sheet metal and comprise spaced apart strips 88 and 90 suitably attached as by means of

nails 92 to the bars 86. The lower portions of the two strips 88 and 90 receive a substantially triangular shaped member 94, one wall 96 of which is vertical and flat while the opposite wall 98 is inclined or wedge-shaped and tapers upwardly from a rather wide base 100 to the apex 102. These wedge-like or triangular spaced members are formed of a single strip of sheet metal folded or bent so that the intermediate portion of the strip forms the apex 102 while the free ends are suitably curved or bent and form the base. These wedge-like members may be held in place between the side strips 88 and 90 by soldering or spot welding. It will be noticed that a curved wall 98 is always adjacent the straight wall 96 of the next contiguous holder. Balls 104 are inserted between two spaced apart holders before they are assembled. The arrangement is shown clearly in Figures 4 and 5. With this construction, when a sheet 106 of light sensitive material is inserted upwardly between one of the flat pieces 90 and the ball, the ball will be moved upwardly to permit the free insertion, but under the action of gravity and the tendency of the sheet to move downwardly, the ball is wedged along the inclined surface 98 and acts to securely hold the sheet in position against the vertical face 96. It will be appreciated that these holders are arranged in pairs on opposite sides of the frame and in the same plane so that the upper opposite corners or tops of a sheet of light sensitive material are securely held so that each sheet will hang vertically. There being a number of pairs of these holders as shown, the support is arranged to hold a plurality of sheets in parallel depending position.

The means for operating the curtain preferably includes upper and lower rollers. The upper roller 108 is mounted on a shaft 110 in the upper part of the cabinet while the lower roller 112 is mounted on another shaft 114 in the lower portion of the cabinet beneath the floor 66. These two shafts 110 and 114 may be arranged in suitable housings 116 and 118 respectively for enclosing the same. The ends of these shafts at one side of the housings are provided with sprockets 120 and 122 over which a chain 124 passes, which chain in turn meshes with a relatively large gear 126 on a shaft 128 journaled in the walls of the main cabinet. This shaft in turn has a handle 130 whereby the chain 124 may be moved to rotate the shafts 110 and 114 in unison to operate the upper and lower rolls together. The curtain 132 is arranged to slide or move in two U-shaped ways 134 and 136 carried on the inner vertical walls 138 and 140 of the cabinet. This curtain may be of any desired material that is not affected by the action of the developing gas; it may be of rubber or rubberized fabric or heavy textile fabric.

such as duck or the like, and sufficiently thick so as to be substantially air-proof or gas-proof. The curtain is fixed to the upper roll 108 about which it normally winds. The lower portion of the curtain is provided with two marginal relatively long straps or integral portions 142 and 144 (see Figure 3) which are attached to the lower roll 112. These straps provide an intermediate portion of the roller 146 which forms a relatively wide cut-out of sufficient width to permit the passage of the truck 76 between the straps 142 and 144 when the curtain is in raised position, it being understood that when the curtain is in such raised position the lower edge of the intermediate portion of the curtain immediately above the recess 146 will lie above the path of movement of the truck while the relatively long side straps 142 and 144 will straddle the truck 85 with their lower ends attached to the lower roller 112. By means of this construction, when the lower roller is operated in one direction the curtain will be lowered by means of the straps winding up on the roller where-as when the upper roller 108 is rotated in its proper direction the curtain will raise. In addition, the lower portion of the curtain is slotted as at 148 and 150 to straddle the driving chains for the truck as herein-after described. In other words, when the curtain is in lowered position as shown in Figure 3, the slots 148 and 150 in the lower edge of the curtain will pass around the driving chains so as to form substantially gas-tight joints with the floor 66 at this point so as to prevent any great amount of ammonia gas passing through into the loading chamber.

In order to move the truck back and forth on the tracks, I provide one end of the developing chamber above the floor 66 with a transverse shaft 152 carrying two sprockets 154 and 156 over which pass two chains 158 and 160. In the loading chamber immediately above the floor, I also mount another transverse shaft 162 on which are similarly mounted two sprockets 164 and 166 over which the chains 158 and 160 pass. The outer end of the shaft 162 is provided with a relatively small gear 168 which meshes with a relatively large gear 170 on a shaft 172. This gear is provided with a turning handle 174 so that when turned the chains 158 and 160 will be operated to shift the truck along the tracks 72 and 74.

In the operation of my improved device, the truck is moved by means of the chains 158 and 160 so that the truck is shifted into the loading chamber after which the curtain 132 is moved downwardly to close communication between the developing and loading chambers. The door 51 is then opened and sheets of light sensitive material are hung from the holders. The door is then closed,

the curtain raised, and the truck moved into the developing chamber. The curtain is then again lowered and the fan 26 is put into operation so that the ammonia gas will be blown from the saturated wicks and will pass from the fan chamber through the directing veins against the wicks and thence will pass into the developing chamber into communication with the light sensitive material. Immediately upon the operation of the fan 26, the light shutters 14 will have opened to permit outside air to pass into the fan chamber as hereinbefore described.

After a sufficient period of development, the motor is then reversed for driving the fan in the opposite direction which immediately and automatically closes the shutters 14 at which time they may be locked by means of the claws 20. The reversal of this fan at once sucks the greater portion of the ammonia gas back into the fan chamber. At this time, the curtain is again raised and the truck carrying the developed material thereon is moved into the ventilating chamber and the curtain is again lowered. Then the ventilating fan 60 in the ventilating chamber is put in operation to remove the occluded gases from the light sensitive material after which it may be discharged through the open door of the loading chamber and the apparatus is then ready for further loading and developing.

By reason of the foregoing, it will be seen that a greater number of sheets of developing material may be simultaneously developed in a very short time by means of the convenient arrangement of the developing and loading chambers and that during the developing operation, the ammonia gas will have but little opportunity to escape into the surrounding air about the cabinet. This is due in the main, to the presence of the shiftable curtain or screen, and secondly, to the construction and operation of the shutters 14 of relatively light material and the means for holding them in closed position, together with the means whereby a large portion of the developing gas may be sucked back into the fan chamber when the fan is reversely rotated.

Having thus described my invention what I claim as new and desire to secure by Letters Patent is:

1. In a developing apparatus, the combination of a cabinet provided with a developing chamber and with a loading chamber, a shiftable curtain adapted to cut off communication between said chambers, a shiftable carrier adapted to support light sensitive material adapted to be shifted from one of said chambers to the other of said chambers when said curtain is shifted to open communication between said chambers, and means in the developing chamber adapted

to flow developing gas against the light sensitive material.

2. In a developing apparatus of the character described, the combination of a cabinet, a shiftable partition in said cabinet adapted when closed to divide the cabinet into separate chambers, a movable carrier in said cabinet adapted to move from one chamber to the other when said partition is moved to permit communication between said chambers, a source of developing gas in one of said chambers, means for blowing said gas on light sensitive material on said carrier in said chamber, and means in the other chamber for ventilating the light sensitive material when placed therein.

3. In a developing apparatus, the combination of a cabinet provided with a developing chamber, a gas generating station communicating therewith, and a loading chamber communicating with the developing chamber, a shiftable curtain adapted to cut off communication between the developing chamber and the loading chamber, a support mounted in said cabinet and shiftable from the loading chamber to the developing chamber, means for blowing developing gas from the generating chamber into the developing chamber and into contact with the light sensitive material on said carrier, and means for withdrawing said developing gas into said generating chamber.

4. In a developing apparatus, the combination of a cabinet forming a developing chamber and a communicating gas generating chamber, means for supporting light sensitive material in the developing chamber, means for projecting developing gas from the gas generating chamber into the developing chamber and for causing the withdrawal of said developing gas from the developing chamber back into said gas generating chamber.

5. In a device of the class described, the combination of a cabinet formed with a developing chamber and a communicating chamber, means for projecting developing gas from said communicating chamber into said developing chamber and into contact with light sensitive material supported therein, and means constructed and arranged to withdraw said developing gas from said developing chamber back into said communicating chamber.

6. In a device of the class described, the combination of a cabinet provided with a developing chamber and a communicating fan chamber having an opening to the atmosphere, a plurality of shutters controlling said opening, said shutters being of relatively light material and automatically shiftable by the creation of an air current in said fan chamber, means for driving said fan in reversed directions, and absorbent means

disposed in the path of movement of the air and saturated with liquid adapted to evolve chemically active developing gas whereby said air current created by the fan 5 will project evolved developing gas onto the light sensitive material.

7. In a device of the class described, the combination of a cabinet formed with a developing chamber, means for supporting 10 light sensitive material in said chamber, means for causing a current of air to pass into said developing chamber to project developing gas against said light sensitive material and means for causing the reversal of 15 the current of air to withdraw the gas from said developing chamber.

8. In a device of the class described, the combination of means forming a cabinet provided with a developing chamber and a 20 loading chamber, a curtain shiftable across said cabinet and adapted to isolate the developing chamber from the loading chamber, a movable carrier mounted in said cabinet and adapted to support light sensitive 25 material and to move from said loading chamber to the developing chamber and back, means for moving said carrier and means for shifting the curtain and means for blowing gases into said developing chamber to develop the light sensitive material therein. 30

9. In a device of the class described, the combination of a cabinet provided with a developing chamber and a ventilating chamber, a fan communicating with the developing 35 chamber, and a fan communicating with the ventilating chamber, means for causing the first fan to blow developing gas into contact with light sensitive material in the developing chamber and means for causing the second fan to project air against the light sensitive material in the ventilating chamber. 40

10. In a device of the class described, the combination of means forming a cabinet provided with spaced apart vertical walls and 45 forming a developing chamber and a ventilating chamber, said walls having vertical guide-ways, a curtain vertically shiftable

and having its marginal edges projecting into said guide-ways to form a substantial air-tight seal, an upper roll upon which said curtain winds, a lower roll, said curtain having its ends connected to the lower roll and said curtain being formed so as to provide an opening in its lower portion when raised, a movable carrier adapted to move along the 50 floor of said cabinet and to shift into and out of the developing chamber and through the opening in said curtain, and means in the developing chamber for developing light sensitive material therein. 55

11. In a device of the class described, the combination of a cabinet, having a floor provided with spaced rails, a wheel truck mounted on said rails and said rails having registering slots therein, a curtain mounted 60 in said cabinet and adapted to raise and lower through said slot to permit the passage of the truck along the floor of said cabinet, and means on one side of the curtain for developing light sensitive material. 65

12. In a device of the class described, the combination of a cabinet having an upper roll and a lower roll mounted thereon, a curtain having its upper end adapted to wind on the upper roll and having marginal 70 straps on its lower end adapted to wind on the lower roll, said straps being spaced apart substantially the width of the cabinet to form a cut out therebetween, a shiftable carrier adapted to move along the floor of 75 the cabinet and to pass between said spaced apart straps when the curtain is in raised position so as to permit the truck to move from one portion of the cabinet to the other, means for operating said rollers for raising 80 and lowering the curtain, means permitting the movement of the truck, means on said truck for supporting light sensitive material and means at one end of the cabinet for projecting developing gas against said light 85 sensitive material. 90

In witness whereof, I have hereunto subscribed my name.

ADOLPH LANGSNER.
